[57] CLAIM

The ornamental design for a front face of a drawer, as shown and described.

DESCRIPTION

FIG. 1 is a front elevational view of a front face of a drawer showing our new design;

FIG. 2 is a left side elevational view, the right side being a mirror image thereof;

FIG. 3 is a top plan view, the bottom view being a mirror image thereof;

FIG. 4 is a top, right side perspective view thereof; and,

FIG. 5 is a bottom perspective view thereof.

The surface or portion of the article not shown in the drawing or described in the specification forms no part of the claimed design.
